UNITED STATES PATENT OFFICE

2,297,243

DIVISION MECHANISM

August Friedrich Pott, Zella-Mehlis, Germany;
Vested in the Alien Property Custodian

Original application September 23, 1931, Serial No. 564,643. Divided and this application June 10, 1937, Serial No. 147,588. In Germany October 2, 1930

3 Claims. (Cl. 235—63)

My invention relates to improvements in calculating machines and more particularly to division mechanism for machines of the Mercedes Euclid type disclosed in my Patent No. 2,143,741, of which the present application is a division.

An object of the present invention is to equip a machine of the type above identified with improved simplified controls enabling the machine to perform automatic division, and is more particularly directed to means to enable the quotient obtained in the performance of a problem in division to remain in the quotient register of the machine, while a succeeding problem in division is being performed, during which second performance, and as the second quotient is being determined, it is automatically subtracted digit by digit from the quotient first obtained, so that at the completion of the second problem in division the amount remaining on the quotient register represents the difference between the first and second quotients.

Another object is to provide division mechanism under control of a special division key to reverse the direction of rotation of the revolutions counter and a quotient difference key to set the division mechanism without effecting a reversal of the direction of rotation of the revolution counter or quotient register with respect to the accumulator, so that a quotient difference is registered on the revolution counter.

Still another object is to equip a machine of the type specified for the performance of automatic division without increasing the standardized overall dimensions of the machine.

Other, and subordinate, objects are also comprehended by my invention, all of which, together with the specific nature of my improvements will be understood when the following description and claims are read with reference to the accompanying drawings.

In said drawings:

Figure 1 is a view in perspective of a Mercedes Euclid calculating machine embodying my improved division mechanism, the cover plate being partly removed to disclose the interior mechanism.

Figure 2 is a view in perspective looking at the rear of the machine.

Figure 3 is a view partly in section and partly in side elevation of the main drive shaft 5 of the machine, the carriage shift and value entering clutches 140 and 143 thereon, respectively, and the reverse gearing between the carriage shift clutch 140 and the carriage C, parts of the drive to the revolutions counter RC, and parts of the

driving mechanism between the value entering clutch 143 and actuators R.

Figure 4 is a view in front elevation of the mechanism shown in Fig. 3,

5 Figure 5 is a view in perspective of the main drive shaft 5 and the clutch parts thereon, the parts being shown disassembled for clearness of illustration,

Figure 6 is a view in side elevation of a reverse 10 gearing for the revolutions counter RC the parts being separated for clearness of illustration,

Figure 7 is a view in longitudinal section of said reverse gearing,

Figure 8 is a plan view illustrating the relation 15 of the parts of said reverse gearing,

Figure 9 is a plan view of a coupling mechanism forming part of the drive between the differential actuators R and the accumulator A,

Figure 10 is a view in side elevation of said 20 coupling mechanism,

Figure 11 is a view in front elevation of parts of the revolutions counter RC and the driving shaft 118 therefor.

Figure 12 is a diagrammatic view of said driving shaft 118 for the revolutions counter RC,

Figure 13 is a view in perspective of the reverse gearing for the carriage C together with parts of the gear conditioning means and other parts associated with said gearing.

30 Figure 14 is a view in perspective illustrating the motor 1, motor contacts 141, 142, the "add" and "sub" keys 7, 8, the means for controlling the carriage shift and value entering clutches 140, 143 by said keys, the means for opening and

35 closing said contacts under control of said keys, the differential actuators R set for addition, the means for conditioning said actuators for addition or subtraction under depression of said keys, the automatic actuator conditioning means, the means for conditioning the revolutions counter RC, and other parts of the machine presently described in detail,

40 Figure 15 is a view in perspective of the special control keys 14, 15, 16, 18 of the machine and parts operated thereby,

45 Figure 16 is a view in perspective of a coupling bar 83 forming part of the automatic actuator conditioning mechanism, a coupling link 81 forming part of the quotient difference division mechanism, and a coupling suspension link 88 for operating said bar and connected to the coupling link first named,

50 Figure 17 is a plan view of the special control keys 14, 15, 16, 18, 19, 20, 21, 23 and a frame 31 in which said keys are mounted,

Figure 18 is a view in perspective of parts of the overdraft mechanism, including the overdraft conditioning ball 126 occupying the position relative to the tens transfer slide determined by the setting of the accumulator for subtraction in a division operation, also a clutch control mechanism, including the clutch control flap 189, and operating connections between said flap and the clutch control shaft 162, also the disabling flap 147 and key locking frame 31, and parts of the mechanism operated by the carriage right shift and left shift keys 15, 14,

Figure 19 is another view in perspective of the clutch control shaft 162 and parts carried thereby, a lever 231 forming part of the carriage 15 clutch 140 conditioning means, and devices for interlocking the clutch control shaft with said lever,

Figure 20 is a detail view of parts of the overdraft mechanism,

Figure 21 is a view in perspective of the conditioning means for the carriage clutch 140,

Figure 22 is a fragmentary end view of the add and subtract conditioning means for the revolutions counter RC the means being shown in normal adding position,

Figure 23 is a similar view with the parts in the position they assume upon depression of the division key 16,

Figure 24 is another similar view with the parts in the position they assume under depression of the quotient difference division key 18,

Figure 25 is a perspective view of the differential actuators R, part of the drive therefor, and the coupling mechanism between the actuators 35 and the accumulator A, and

Figure 26 is a view in transverse section taken on the line 26—26 of Fig. 1 looking in the direction indicated by the arrows.

GENERAL ORGANIZATION

The usual tiltable carriage C, surmounting the frame F, is mounted in any suitable manner for denominational step by step shift to the right and to the left, in the rear of the usual denominational rows of value keys K (see Fig. 1). The carriage C supports an accumulator A and a revolutions counter RC visible through sight openings S in a cover plate 17' of the carriage C. The machine is power driven by a motor 1 (Figs. 2 and 14), the armature shaft of which is geared to a main drive shaft 5 by a worm 3 and worm gear 4.

At one side of the value keys K is a group of special control keys, (Fig. 1), including addition and subtraction keys 7 and 8, designated "Add" and "Sub" respectively, a keyboard clearing key 9 designated "R_K", an accumulator clearing key 10 designated "R_A", a revolutions counter clearing key 11 designated "R_{RC}", and a repeat lever 12.

On the opposite side of the keyboard is another group of special control keys, including a pair of carriage right shift and left shift keys 15 and 14, respectively, a division key 16, and a quotient difference division key 18.

The machine, as shown, is also equipped with a multiplication lever 22, plus and minus computing keys 20 and 19, respectively, a correction key 21 and a minus multiplication key 28. The last mentioned keys 19, 20, 21, 28, the lever 22 together with the keys 7, 8, 9, 10 and 11 form per se no part of the present invention and need merely be identified in passing.

Value setting up mechanism

The value keys K operate value setting up mechanism forming the subject matter of U. S. Patent No. 1,935,858 to which attention is invited for an understanding of the details thereof. Briefly described, said mechanism comprises several denominational series of settable value entering gears 300, 301, 302, 303, 304, (Fig. 25), one series for each row of value keys K. These gears are splined upon suitably journaled shafts 305, extending longitudinally of the machine each of which shafts has fixed thereon a driving gear 306 for operating the corresponding denominational wheel of the accumulator A, as presently described.

The value keys K, when depressed in the setting up of an item, are locked depressed by key locking bars 149, one for each row, tensioned for movement to locking position and movable upon depression of one key of a related row to release another key of said row, all as disclosed in the above noted Patent No. 1,935,858.

The differential mechanism

As is well known, the Mercedes Euclid calculating machine is an adding mechanism equipped with differential actuating mechanism conditionable under control of the "add" and "sub" keys 7 and 8 to add either the actual or the complementary values set up in the value setting up mechanism. For a detailed disclosure of the differential actuating mechanism reference may be had to U. S. Patent No. 1,011,617. For present purposes it may be explained that said mechanism comprises a series of ten actuator racks, designated as a unit at R in Fig. 25, reciprocable transversely of the machine, and with which the before described value entering gears 300 to 304 mesh in their different set positions. The racks R are conditionable for movement in different degrees on their forward strokes to rotate said gears in accordance with either the actual or the complementary values of the depressed value keys K. The conditioning of the actuators R for addition is accomplished by locking one outside rack 100 against movement and by similarly locking the other outside rack 105 for subtraction. To this end, a locking bolt 99 arranged transversely to the rack, is slidably mounted in any suitable manner for setting in opposite directions to interlock with said racks 100 and 105, respectively, by projection of one or the other of its ends into apertures 100^a and 105^a in said outside racks, respectively. The bolt 99 forms part of an actuator conditioning or add and subtract conditioning means to be described.

Accumulator

The accumulator A comprises the usual denominational accumulator wheels 307 (Figs. 1, 25 and 26) bearing on their peripheries the series of symbols "0" to "9" and fast upon hollow shafts 311 suitably journaled in the carriage C. The hollow shafts 311 have fast thereon gears 310, driven by the before-mentioned coupling mechanism to be described. Associated with the accumulator wheels 307 is a tens transfer mechanism (Figs. 25 and 26), including transfer dogs 312, the dog 132 (Fig. 18), located only in the highest order. This special dog will be particularly described under the title "Division mechanism." All the transfer dogs 312, 132 are operated in sequence upon each operation of the machine, by a series of cams 192 (Figs. 9 and 75 10), spirally arranged about a driven shaft 193.

Whether or not the operation of the respective dogs 312 shall be effective is determined by the positioning or non-positioning of slides 312^a under control of the accumulator into the paths of the upper beveled ends of the dogs. The dogs are restored to their home positions by a bail 312^b. The transfer mechanism, being well known and understood in the art, need not be entered into herein. For a detailed disclosure thereof attention is directed to U. S. Patents Nos. 1,011-10 617 and 1,566,961. The usual knobs 311^a provide for manually setting values in the accumulator wheels 307 at will.

The revolutions counter

Suitably journaled on the denominational shafts 311, (Figs. 1 and 26), in the rear of the accumulator wheels 307, are denominational revolutions counter wheels 300^a each having on its periphery the series of symbols "0" to "9" reversely arranged relative to the symbols on its related accumulator wheel 307. The counter wheels 300^a are each rotated step by step through the medium of a subjacent spur gear 301^a (Fig. 26) having fast thereto, concentrically thereof, a gear 302^a meshing with a similar gear 303^a fixed to said counter wheel 300^a concentrically thereof. Each gear 302^a has fast thereon a transfer tooth 304^a which, upon rotation of a counter wheel 300^a of lower order from "0" to "9" or vice versa, 30 engages a transfer gear 305^a in the counter wheel of next higher order to impart a half step of rotation thereto. Suitably journaled in the main frame F (Figs. 1, 11, 12 and 26), lengthwise of the revolutions counter RC and below the spur 35 gears 301^a, is a counter driving shaft 118. The counter driving shaft 118 is equipped to complete the transferring operations in said revolutions counter RC as follows: Adjacent one of its ends, the shaft 118 is provided with a pair of 40 opposed transfer blades 212, 212^a spaced part circumferentially of said shaft and inclined relatively to the longitudinal axis thereof. Located along the shaft 118 from said blades, at equidistantly spaced intervals, are rib-like 45 transfer teeth T. The blades 212, 212^a are so designed that in the different denominational positions of the carriage C, one of the other of said blades, during each rotation of said shaft in one direction or the other, imparts a complete 50 step of movement in like direction to the particular spur gear 301^a with which it is at that time operatively related. The spur gear 301^a, in turn, transmits this one step of movement to its corresponding counter wheel 300^a. Because of the automatic step by step movement of the carriage relatively to the blades 212, 212^a, a one 55 step movement is imparted to successive counter wheels 300^a. It will, of course, be understood that the counter wheels 300^a are rotated in opposite directions for addition and subtraction respectively. The transfer teeth T are so arranged that the end portions thereof are disposed in oppositely related spirals around said shaft 118. One end of the transfer teeth T namely 213 to 219 are effective in one direction of rotation of said shaft 118 to impart half a step of movement to the spur gears 301^a of these counter wheels 300^a to which half a step of transfer movement has been imparted by transfer tooth 304 whereby transferring as regards said wheels is completed. The other ends of said teeth T namely 213^a to 219^a (Fig. 12) are effective in the other direction of movement of said shaft 118 to similarly operate said spur gears 301 75

and the related counter wheels 300 in the opposite direction. In Fig. 12 a diagrammatic representation of the blades 212, 212^a and the teeth T has been shown. It is to be understood that the blades 212, 212^a and the transfer teeth T are spaced around the shaft 118 so as to leave a clear, unobstructed path for the movement of the spur gears 301^a in the normal position of said shaft as the spur gears and carriage shift in either direction denominational. The shaft 118 is yieldingly held in its normal position by means of a locking bolt 118^a mounted in brackets 118^b and tensioned by a spring 118^c to engage a notch 118^d in said shaft 118.

15

CARRIAGE SHIFT RIGHT AND LEFT

The carriage C is shifted to right and left through the medium of a carriage shift clutch 140 (Figs. 3 and 5) on the main drive shaft 5. The carriage shift clutch is of the single revolution type and comprises opposed housing members 140^a, 140^b loose on said shaft and between which a trip pawl 197 is suitably pivoted to engage and disengage the ratchet tooth 167 of a sleeve 168 fast on said shaft 5. A suitably arranged spring 197^a tensions said pawl 197 to normally engage the same with said tooth, but the pawl is normally held in idle position by contact with a clutch-tripping dog 161, as hereinafter more fully explained. The carriage shift clutch 140 is operatively connected to the usual carriage propelling rack 17^a (Fig. 2) on said carriage by means of a carriage driving gear 198 on the member 140^a and reverse gearing between said gear 198 and rack 17^a as follows. Suitably journaled in the main frame F is a sleeve 227 (Fig. 13) having fast on one end thereof a pin gear 227^a cooperating with said rack 17^a to shift the carriage C step by step. A detent lever 227^b cooperates with the pin gear 227^a for a purpose unimportant to the present invention and which, therefore, requires no explanation. Rotatably mounted on the sleeve 227 is a pair of carriage reversing gears 133, 134 constituting right shift and left shift gears, respectively. The gear 133 meshes directly with the carriage driving gear 198. The gear 134 is driven by said gear 198 through the medium of an idler gear 199 (Fig. 3). A draw key 139, (Fig. 13), is slidably mounted in the sleeve 227 for endwise setting in opposite directions, respectively, to alternately couple said gears 133, 134 to said sleeve by means of a key bit 138 thereon sliding in a key way 227^c in said sleeve and in key ways 133^a and 134^a in said gears, respectively. As will be understood, the draw key 139 in its opposite settings, conditions the carriage reverse gearing for right shift and left shift movement of the carriage.

The draw key 139 is set under control of the carriage right shift and left shift keys 15 and 14, and also by the carriage C, through the medium of a swingably mounted gear conditioning unit (Figs. 2 and 21) comprising three levers 231, 233, 226, at the rear of the machine, interconnected for unitary swinging movement in opposite directions and also for relative movement. A link 203 connects the lever 226 to the draw key setting lever 224 operatively connected to said keys 138, 139, so that movement of said lever in left and right directions shifts said draw key 139 (Fig. 13) into its opposite settings. The draw key 139 is normally set to couple the carriage left shift gear 134 to the sleeve 227, in other words to condition the carriage reverse gearing for left hand shift of the carriage C, by means of a rocking

bell crank 136, (Fig. 21), operatively connected to lever 233, by means of a bolt 239, and tensioned by a suitably connected spring 223. The carriage right shift and left shift keys 15 and 14 are operatively related to said gear conditioning unit by means of a pair of bell crank levers 230 and 263, respectively, adapted to swing said unit in opposite directions to condition the carriage reverse gearing for right and left shift of said carriage C. A link 228 operatively connects the carriage right shift key lever 90 (Fig. 15) to its related bell crank 230. A similar link 262 operatively connects the carriage left shift key lever 261 to its related bell crank lever 263. The condition of the carriage reverse gearing is reversed in the left and right hand limits of movement of the carriage C, respectively, by means of left and right hand tappets 135 and 137 (Fig. 21) adapted, respectively, upon movement of said carriage into said limits of movement to rock said bell crank 136, and hence the conditioning unit, in opposite directions.

The pair of bell cranks 230, 263 (Fig. 18) are provided with fingers 233^a, 264, respectively, which, upon depression of said keys 15 and 14, contacts with lateral crank arms 234, 265, (see Figs. 18 and 19), of a crank member 235 fast upon a transverse clutch control rock shaft 162, to rock said shaft in one direction, that is to say, counter-clockwise as viewed in Figs. 14, 18 and 19. Such rocking of said shaft 162 effects engagement of the carriage shift clutch and also starts the motor 1 by means to be hereinafter described under the succeeding heading "Control mechanism."

It may be mentioned that the clutch control rock shaft 162 is interconnected with the lever 231 of the described conditioning unit for the carriage reverse mechanism by means of the angular tongue 235^a, 235^b pivoted on said crank 235 and the projection 231^a on said lever 231, during continued depression of the carriage right shift key 15 so that the carriage C continues to shift in the right hand direction until said key is restored to normal. The carriage right shift key, if in depressed position, is restored by the carriage as it reaches the limit of its travel to the right, through contact of the carriage left hand tappet 135 (Fig. 21), with the upper end of the bell crank lever 136. The left hand tappet 135 rocks the bell crank lever 136 clockwise, and such lever, through the pin-and-slot connection 239, rocks the lever 233 counter-clockwise. The horizontal arm of the bell crank 230 is connected with the carriage right shift key 15 by link 228. As the bell crank 230, upon depression of the carriage right shift key, rocks the lever 233 clockwise and maintains it in such position, movement of the bell crank 136 in clockwise direction restores the carriage right shift key 15 to normal.

The carriage left hand tappet 135 imparts a movement to the lever 233^a of such extent as to rock it together with the associated levers 226 and 231, to condition the carriage reverse gearing for left hand shifting operation. Also under continued depression of the left shift key 14, similar results are obtained as regards travel of the carriage and return of said key. However, these features of the carriage right shift mechanism form, per se, no part of the present invention, being the subject matter of my copending application Serial No. 147,587, filed of even date herewith, and detailed description thereof, is therefore thought to be unnecessary herein.

DRIVE TO ACCUMULATOR

Beside the carriage shift clutch 140 is a value entering clutch 143 (Figs. 3, 5) identical in construction with the carriage shift clutch and including housing members 143^a, 143^b rotatable on said shaft and a trip pawl 164 tensioned by a spring 165 to normally engage the before mentioned ratchet tooth 161. The same clutch tripping dog 161 normally engages the trip pawl 164 to hold it idle. One clutch member, 143^a, is operatively connected to a suitably journaled jack shaft 183 (Figs. 3 and 9) by means of a pair of intermeshing gears 181, 182 fixed to said member and jack shaft, respectively. A crank disc 184, fast-on said shaft 183, and a pitman rod 158, (see also Fig. 14), are operatively connected to the differential actuator racks R to impart a reciprocatory cycle of movement thereto during each revolution of the value entering clutch 143. For a detailed disclosure of the operating connections attention is directed to the previously noted Patent No. 1,011,617. Subjacent to the accumulator A is a suitably journaled tens transfer shaft 193, (Figs. 3, 9 and 10), to which the jack shaft 183 is geared by bevel gears 182^a, 182^b. The accumulator transfer shaft 193 is provided with transfer cams 192 operative upon the before mentioned transfer dogs 312 (Fig. 25) as described in Patents Nos. 1,011,617 and 1,566,961.

Intermediate the driven gears 310 of the accumulator A and the actuator racks R is the before-mentioned coupling mechanism comprising a series of denominational gears 308 rotatably mounted in a longitudinally split shaft 309 (Figs. 9, 10, 25) suitably journaled in the main frame F for rotation to intermittently mesh said gears 308 with said gears 310 and with the driving gears 306 of the value setting up mechanism. The shaft 309 is rotated intermittently by the transfer shaft 193 through the medium of a pin gear 193^a fast on the latter, and meshing with a suitably mounted Geneva gear 193^b, and a gear train 193^c (Fig. 10) between said Geneva gear 193^b and the shaft 309. For the present purposes, it is sufficient to explain that the described coupling mechanism provides for coupling the gears 306 and appropriate gears 310 during each forward stroke of the actuator racks R and uncoupling the same during the return stroke of said actuators.

DRIVE TO REVOLUTIONS COUNTER

Intermediate the transfer shaft 193, (Figs. 4 and 8), and the revolutions counter driving shaft 118 is a counter driving, reversible gearing as follows. Fast on said shafts 193 and 118 are gears 193^d, 118^e, respectively. Suitably journaled in the main frame F is a sleeve 117, (Fig. 6), having a fixed gear 117^e thereon meshing with gear 118^e. Rotatably mounted on the sleeve 117 is a pair of forward and reverse driving gears 209, 208, (see also Fig. 7), for use in positive and negative operations, respectively. The gear 193^d meshes with the reverse driving gear 208 and also drives the forward driving gear 209 by way of twin idler gears 209^a, 209^b. A draw key 114 slidably mounted in the sleeve 117 is settable in opposite directions therein to couple said gears 209, 208 to said sleeve, respectively, through the medium of a key bit 115 on said key, key ways 209, 208 in said gears, respectively, and a key way 117^b in said sleeve. The draw key 114 in this instance is also settable into an intermediate position (Fig. 7) wherein both gears 209,

208 are uncoupled from said sleeve 117, in which position the drive to the revolutions counter is disabled for a purpose which will be understood. The draw key 114 is set by means hereinafter described.

ADD AND SUBTRACT CONDITIONING MEANS

The machine is equipped with add and subtract conditioning means which will be briefly described at this point.

The actuator racks R are conditioned for addition and subtraction through the medium of a transverse rock shaft 107 (Figs. 14, 22 to 24) having fast thereon an actuator conditioning crank 102, one end 102^a of which is operatively connected to the before mentioned locking bolt 99 to set the same in opposite directions upon rocking movement of said shaft 107 in opposite directions, respectively. The opposite end of said crank 102 has secured thereto a lateral stud 101 for a purpose to be described. The "add" and "sub" keys 7 and 8 are operatively connected to said shaft 107, through the parts 240, 241, 242, 243 and 240, 241, 242 and 243, respectively, so that said shaft is rocked in one direction or the other upon depression of the appropriate key.

Coincidentally with the conditioning of the actuator racks R for addition or subtraction, the revolutions counter RC is correspondingly conditioned by means of a vertically disposed double crank 108 fast intermediate its ends on the shaft 107, a draw key setting bell crank 111, (Figs. 6 and 25), pivoted at a fixed point, by means of a screw 210, and operatively connected to said draw key, and a draw bar 96 pivoted at one end to said bell crank 111 for vertical movement thereon and to the other end of which draw bar said crank 108 is operatively connected as follows. The crank 108 has formed therein a pair of upper and lower substantially triangular apertures 316, 314 disposed upon opposite sides of said shaft 107 and terminating adjacent opposite ends of said crank 108 in upper and lower notches 291, 120, respectively. The draw bar 96 is provided with upper and lower studs 290 and 110, respectively, so arranged that upon vertical movement of said draw bar in opposite directions, said studs 290, 110 may be engaged with said upper and lower notches, respectively. Under normal adding and subtracting conditions, the draw bar 96 is held elevated by means presently described, with its upper stud 290 engaging the upper notch 291 whereby, upon rocking movement of the shaft 107 in opposite directions, the draw key 114 is set in opposite directions to condition the counter reverse gearing for addition and subtraction as will be understood. Between the studs 290, 110, the draw bar 96 is provided with a central slot 96^a of hour glass shape into which one end of the shaft 107 extends, said slot permitting vertical movement of the draw bar 96 and cooperating with said end of shaft 107 to limit relative movement of the crank 108 and draw bar 96 in a manner immaterial to the present invention.

The carriage shift and value entering clutches 140, 143 are controlled by means of a clutch tripping dog 161 (Figs. 3, 14) fast upon the before mentioned clutch control rock shaft 162 and normally occupying an intermediate position in which both clutch pawls 197 and 164 are tripped and said clutches thereby disengaged. The clutch control shaft 162 is mounted to rock in opposite directions to carriage shift and value entering clutch engaging positions, respectively, to effect, in a manner which will be understood,

alternate engagement of said clutches 140, 143. A pair of segmental combs 281, 280 (Fig. 5), on the clutches 140, 143, respectively, block movement of the tripping dog 161 to said positions 5 until which ever clutch is engaged has completed a full revolution.

The clutch control shaft 162 is rocked in opposite directions under control of the "add" and "sub" keys 7 and 8 (Fig. 5), through the medium of a key locking ball 80. The ball 80 is swingable in the clockwise and opposite direction on a transversely extending shaft 57 (Fig. 25), suitably mounted for rocking movement for a purpose to be explained. The key locking ball 80 (Fig. 25), in its forward swinging movement engages depending arms 148, on the key locking bars 149 and blocks movement of the latter to key releasing position. In its forward movement said ball 80 cooperates with an arm 150 (Fig. 14), on a tensioned yoke 151 vertically swingable on a transverse shaft 152, and swings said yoke 151 in one direction in opposition to the tension exerted thereagainst by a spring 151^a. Such movement of yoke 151 swings a clutch control rocker 160, journaled on the clutch shaft 162, in one direction from a normal position, by means of a link 153 connected to said yoke and to a depending arm 154 on said rocker 160 (Fig. 14). The rocker 160 is operatively connected by a tension spring 159 to a lateral arm 161^a of the clutch tripping dog 161 so that such swinging of said rocker acts to urge the dog 161 into value entering clutch engaging position. An arm 157 on the rocker 160 overlying the laterally bent arm 161^a of the dog 161, rocks said dog 161 into intermediate position upon movement of said rocker 160 back to normal position in a manner described in the Patent 2,143,741.

40 The motor 1 is energized by means of a pair of fixed and movable contacts 142, 141, the latter carried by a resilient contact carrier 180. The contacts 141 and 142 are opened and closed under control of a cam 178, 179 on the main drive shaft 5, a contact opening and closing lever 176 pivoted intermediate its ends, by means of a rivet 175, on an arm 172 of a carrier 173 for movement thereon by said cam, and a suitable spring 177 urging said contact controlling lever into contact with said cam. The carrier 173 is pivotally mounted on a shaft 85 for movement against the tension of a spring 174, to shift the lever 176 from a normally ineffective to an effective position. Upon swinging movement of the clutch control rocker 160 in the direction above indicated, an arm 169 thereon engages a roller 170 on said carrier and swings the latter in the proper direction to shift the lever 176 to effective position.

60 The key locking ball 80 is swung forwardly by depression of the "add" and "sub" keys 7 and 8 through the medium of a vertically swingable and laterally shiftable lever 255 depressible by either of said keys through the medium of studs 7^a, 8^a on the key levers thereof, respectively, overlying said lever 255 in the normal position of the latter. The lever 255 is pivotally mounted on a stud 255^c projecting from the adjacent right hand side frame of the machine.

70 A suitably connected spring 255^a tensions the lever against movement from normal position. The spring 255^a normally holds the rear end of the lever 255 upwardly. Alongside the lever 255 is a slide 256 endwise settable in opposite directions by a repeat key lever 12, the slide also being

laterally shiftable. The lever 255 and slide 256 are coupled together for lateral movement in unison by a headed stud 255^b on the rear end of the lever entered in a bayonet slot 256^a in the slide 256 to support the latter at its rear end, and enable independent swinging and setting of the lever and slide, respectively. In the rearward position of said slide 256, a cam 184^a on the crank disc 184 shifts said slide and lever 255 laterally at the end of a single cycle of operation of the machine so that said lever clears the stud 7^a or 7^b of whichever key 7 or 8 is held depressed, whereby said lever is free to return to normal position under the tension of its spring 255^a. In the opposite setting of said slide 256, the cam 184^a is ineffective thereagainst and the machine executes repeat operations as long as a key 7 or 8 is held depressed. It will, of course, be understood that coincidentally with the return of the lever 255, the key locking bail 80 is returned to normal position by the tensioned yoke 151, the rocker 160 is likewise returned to normal position by said yoke as described in the Patent 2,143,741 thereby swinging the clutch tripping dog 161 to its intermediate position in which both clutches 140, 143 are tripped and the carrier 173 is released by the arm 169 of said rocker 160 for return to normal position by its spring 174, whereby the motor contacts 141, 142 are opened in a manner which will be clear without detailed explanation.

DIVISION MECHANISM

The key lever 42 of the division key 16 is pivoted on a short transverse shaft 24 (Fig. 17) for depression against the tension of a suitably connected spring 45, (Fig. 15). A guide plate 29 establishes the normal position of said lever. Alongside said key lever 42 (Fig. 15) and also pivoted on the shaft 24 is a bell crank rocker 50 having a lateral lug 48 underlying said lever 42. A link 55 (Figs. 15 and 25) operatively connects said rocker 50 to a crank 56 fast on one end of the before mentioned shaft 57 which, through said link 55 and crank 56 and rocker 50, is rocked by depression of said key lever 42 for a purpose presently clear. Fast on the opposite end of the shaft 57 is another crank 95 having a stud 97 thereon engaging a slot 98 in the before mentioned draw bar 96, whereby said bar is supported for vertical movement by said crank 95 relative to the before mentioned crank 108 and is also longitudinally movable relative to crank 95 by crank 108. Also alongside the key lever 42 (Fig. 15), and pivoted on the shaft 24 is a bell crank lever 62 and a lever 59 for operating the same, the lever 59 having a lateral lug 58 underlying the key lever 42 whereby depression of said key lever 42 rocks said lever 59. A tension spring 61 yieldingly connects the lever 59 to said lever 62 so that the bell crank lever 62 is rocked with the lever 59 under depression of the key lever 42, against the tension of a suitably connected spring 71.

The purpose of the yielding connection between said levers 59 and 62 will later be explained. Cooperating lugs 63 and 64 on opposed ends of said levers 59 and 62 limit the relative movement of said levers to one another under the urge of the spring 61.

One end 65 of the bell crank lever 62 is operatively related to a rocking control bail 66 disposed transversely of the machine and swingably mounted therein in holes 66^a. A suitably

connected spring 67 tensions the bail 66 against movement by the bell crank lever 62. On one end of the bail 66 carries an arm 77 having a roller 78 thereon overlying a crank arm 79 extending from the before mentioned key locking bail 80. The arrangement of the bails 66 and 80 is such that upon rocking of the bail 66 by the bell crank lever 62, the key locking bail 80 is rocked counter-clockwise as viewed in Figs. 14 and 25, into its key locking position. As previously explained under the heading "Add and subtract conditioning means" said bail 80 is connected to the clutch control rocker 160 to swing the same, tension the spring 159 and urge the clutch control dog 161 into value entering clutch engaging position.

The bell crank lever 62 forms part of an automatic value entering conditioning mechanism best shown in Figs. 13, 14, 15. Said mechanism includes a transverse rock shaft 85 having a pair of crank arms 84 and 203 fast upon its opposite ends, respectively, an eccentric 220 fast on the right shift gear 133 of the carriage reverse gearing, a pitman rod 202 connecting said eccentric to the crank arm 203, and a forwardly extending coupling bar 83 pivotally connected to the crank arm 84 to swing vertically thereon for coupling to the stud 101 of the actuator rack conditioning crank 102 before mentioned. The coupling bar 83 is provided with a V-shaped notch 103 in its under edge overlying said stud 101 and adapted to cam said stud 101, upon downward movement of said bar into engagement with a seat 106 towards which the conveying walls of the V-shaped notch lead, whereby said bar 83 is coupled to said crank. The purpose of camming the stud 101 will be explained subsequently. The coupling bar 83 is swung vertically into and out of coupling position through the medium of the bell crank lever 62 to which said bar is connected by a suspension link 81 pivoted to the lever 62, by means of a rivet 82, and to the coupling bar 83 by means of a rivet 82^a, (Figs. 15, 16). As will be more clearly explained subsequently, the eccentric 220 rocks the shaft 85 to reciprocate the coupling bar 83 whereby the actuator rack conditioning crank 102 is oscillated to reciprocate the locking bolt 99 and thereby alternately condition the actuator racks R for addition and subtraction. Incidentally, the shaft 107 is rocked, as will be apparent, and the revolutions counter RC conditioned for positive and negative operations, alternately, all as described in detail in connection with the subsequent description of divisional operations.

The automatic actuator rack conditioning mechanism so far described also conditions overdraft mechanism comprising the following. Pivotally and slidably mounted on the left hand end of the carriage C, on a short shaft 129 (Fig. 18), extending from front to rear of said carriage, is a horizontally disposed overdraft flap 128 slidable on said shaft into two different positions relative to the transfer slide 132 of highest denomination of the accumulator A. The overdraft flap 128 (Figs. 18, 20) is provided along its right hand edge with a pair of laterally spaced lugs 201, 130 of different lengths adapted, in the different positions of said flap, to be aligned with and engaged by an offset and recessed lug 131 on the transfer slide 132 under different conditions obtaining in said register, whereby the left hand edge of said flap 128 is rocked downwardly by said transfer slide. It will be remembered that

the transfer slides 312 (Fig. 25), and 132 (Figs. 18 and 20), are operated at each operation of the value-entering clutch mechanism 143, through the trains of gears (Fig. 3), 181, 182, 182^a, 182^b, shaft 193 (see also Figs. 9 and 10), and cams 192. Unless a transfer operation is required, the upward projection of these transfer slides 312, 132 is idle. With this in mind, therefore, it is obvious that the special transfer slide 132 on its upward thrust, may or may not strike the lugs 207, 130 of the overdraft flap 128, depending upon two conditions, namely, the position of the adjustable flap on its rod 129, and secondly, whether or not the special transfer slide itself has been adjusted into transferring position. In the present instance, the special transfer slide 132, when conditioned to effect a transfer operation, as in the case of an overdraft, will contact one of the lugs 207, 130 whereas when the transfer slide 132, in a non-transfer position, is merely projected upwardly incident to the operation of the machine, it may or may not contact the other of the lugs to rock overdraft flap 128, depending upon the adjusted position of the flap, as will be more fully explained hereinafter. An upright overdraft conditioning or flap-adjusting lever 126 is suitably pivoted on the carriage C for rocking movement forwardly and rearwardly, one arm of the adjusting lever being forked to engage and slide said flap into its different positions, respectively.

The overdraft conditioning lever 126 is rocked by means of an overdraft conditioning bail 124 pivotally mounted in the machine to rock about a horizontal axis 125, the bail extending alongside the carriage C throughout the length of travel thereof. The lower end of the flap-adjusting lever 126 is also forked to slide along said bail 124 during travel of said carriage. The overdraft conditioning bail 124 is rocked by means of an upright lever 123 pivoted intermediate its ends on a fixed part of the machine and operatively connected at its upper end to said bail. The lever 123 is rocked by means of the actuator rack conditioning crank 102, to the stud 101 of which said lever is connected by means of a link 121 paralleling the coupling bar 83.

Alongside the overdraft conditioning bail 124 and rocking about the axis 125 thereof, is a clutch control flap 189 terminating at its left hand end short of the limit of travel of the carriage C and consequently of the left hand end of the bail 124. The clutch control flap 189 is operatively connected to the clutch control shaft 162 by means of a pair of opposed lever arms 190, 186 on said flap and shaft, respectively, and connected together by a slot and pin connection 187, 188, the arrangement being such that downward or clockwise, (Fig. 18), rocking of the flap 189, rocks the clutch control shaft 162 counter-clockwise and consequently the clutch control dog 161, to effect engagement of the carriage shift clutch 140 against the tension of the spring 159.

The clutch control flap 189 is rocked downwardly by the overdraft flap 128 through the medium of an overdraft slide 191 (Fig. 20), of plunger like form suitably mounted on the carriage C for vertical sliding movement against the tension of a suitably connected spring 195 (Fig. 20). A screw 129^b and a slot 129^a in said slide 191 limit upward movement of the latter. The overdraft flap 128 is operatively related to said slide 191 by a laterally extending lug 194 overlying the upper end of said slide. The clutch control flap 189, in the normal position of the

clutch control shaft 162, is spaced from the overdraft slide 191 to movement of said flap 189 counter-clockwise, (Fig. 18), without operating slide 191 when said shaft 162 and the clutch control dog 161 are rocked in a direction to effect engagement of the value entering clutch 143.

At the left hand end of the clutch control 189 is a disabling rocker 147 rocking vertically about the axis 125 of said flap 189 and adapted to be depressed by the overdraft slide 191 when the carriage C is at its left hand limit of movement. The disabling rocker 147 is operatively connected by a depending arm 146 and a link 145 to a bail-like special key locking frame 31 (see also Fig. 15), pivotally mounted for swinging movement into and out of key locking position. A suitably connected spring 32 urges the key locking frame 31 toward locking position and tensions said rocker 147 against depression. In its locking position the frame 31 engages a notch 47 in the division key lever 42 and locks said lever in depressed position. Depression of the disabling rocker 147, by the plunger 191, swings the key locking frame 31 to unlocking position, whereupon the division key lever 42 returns to normal position, thereby terminating the operation of the machine in a manner presently described in detail.

QUOTIENT DIFFERENCE DIVISION

The key lever 23 of the quotient difference division key 18 is pivotally mounted on the before mentioned shaft 24, adjacent to the division key lever 42, for depression against the tension of a suitably connected spring 35. The key lever 23 is designed to operate a rocking yoke 40 having two arms 39 and 41 extending alongside the key lever 23 and the before mentioned lever 59, respectively. The yoke arm 39 is provided with a lateral lug 38 underlying the key lever 23 whereby, when said lever is depressed, the yoke is similarly operated. The yoke arm 41 overlies a lateral lug 58 on the lever 59, whereby said arm operates the latter in the same manner as the division key lever 42, to rock the bell crank lever 62. The before mentioned suspension link 81 forms a part of the quotient difference division mechanism in that it is adapted to couple the bell crank lever 62 to the carriage right shift key 15 so that under depression of the quotient difference division key 18, said carriage right shift key 15 is depressed prior to complete depression of said quotient difference division key 18 as and for a purpose explained as this description proceeds. To this end, said suspension link 81 is provided with a lateral lug 86 (Figs. 15 and 16) which is designed to seat in a notch 93 provided in one edge of a coupling link 88 pivotally suspended, in the hole 89, from the key lever 90 of the carriage right shift key 15 alongside said link 81. A tension spring 91 extending between and suitably connected to the lower ends of said links 81 and 88 urges the same in a direction to enter lug 86 in the notch 93. Upon depression of the division key 18, certain conditions hereinafter specified obtaining, the link 81 is swung in one direction by the coupling bar 83 under control of the eccentric 220 (Fig. 13) to move the lug 86 out of the notch 93, then swung back with the lug 86 below the end of the link 88 by the before described lowering of the coupling bar 83, (due to continued depression of the division key 18 which maintains the rear arm of the bell crank 62 depressed). The link 81 is subsequently moved up-

wardly by elevation of the coupling bar 83, upon the release of the division key 16, to reengage the lug 86 with said notch 93. To facilitate such reengagement, the lower end of the link 88 is provided with a cam edge 237 coacting with the lug 86 to cam the lug into a position to enter said notch 93 under the urge of the spring 91. A stop lug 92 on the link 88 engaging a fixed part of the machine, holds the link 88 stationary against the action of the spring 91 during such camming action and also during swinging movement of the link in said direction.

OPERATION IN DIVISION

In the performance of division, for instance in dividing 390,625 by 625, the carriage C is, preferably, first shifted to the limit of its right hand position by depression of the carriage right shift key 15. The manner in which said carriage is shifted will be understood from the previous description of the carriage drive. The dividend "390,625" is now entered in the accumulator A, preferably in the six value wheels 507 of highest denomination. The divisor "625" is then set up by value keys K corresponding in denominations to those of the three highest digits of the dividend. It is not, as will be understood, necessary to enter the dividend and set up the divisor in the denominations indicated. However, the procedure described will suffice for the purpose of illustration. When the carriage C is nearly at the limit of its right hand travel, the condition of the carriage reverse gearing was reversed by coaction of the tappet 135 (Fig. 21) and the bell crank 136, whereby the before-described gear conditioning unit was swung in a direction to cause the left shift gear 134 (Fig. 12), to be coupled to the sleeve 227.

The division key 16 (Fig. 15), is next depressed, the key locking frame 34 coacting with the notch 47 in the division key lever 42 to lock said key down, as will be clear, against the urge of the spring 45. In the depression of said key 16 the lever 42 thereof acts on the lug 48 of the rocker 50 and rocks the latter clockwise, as viewed in Fig. 15, round the shaft 24 against the tension of the spring 53. The rocker 50, through the depending arm 52 thereof, the crank arm 56 (Fig. 25) and the link 55, rocks the shaft 57 and crank 95 thereon clockwise, as viewed in Figs. 14, 15 and 25. Coincidentally with the movement of the rocker 50, shaft 57 and crank 95, said key lever 42, by engagement with the lug 58, rocks the lever 59 clockwise, whereby, through the connecting spring 61, the bell crank lever 62 is also rocked clockwise, the suspension link 81 thereon lowered and the recessed portion 103, 106 of the coupling bar 83 lowered into engagement with the stud 101 of the crank 102, thereby coupling the automatic actuator rack conditioning mechanism to the state control shaft 107. If the lock bolt 99 is already set to condition the actuator racks R for addition, the camming edge 103 of said bar 83 engages the stud 101 of the crank 102 and moves said crank and the locking bolt 99 into its opposite setting, to thereby condition said actuator racks R for subtraction, said stud 101 entering the seat 106 of said bar 83, whereby the latter is coupled to the crank 102. During such camming of the crank 102, the control shaft 107 and the double crank 108 are rocked counter-clockwise, as viewed in Figs. 14, 22 to 24, from their adding positions illustrated in Fig. 22 into the subtracting positions, shown in Fig. 23. It should be stated at this point that under adding

conditions of the accumulator the upper stud 290 of draw bar 96 engages the upper notch 291 of double crank 108. As a result of the coincidental rocking of the cranks 95 and 108 by operation of the divisions key, the draw bar 96 is moved downwardly by the pin and slot connection 97, 98 to crank 95 to disengage the upper stud 290 from the upper notch 291 of said crank 108. During downward movement of said draw bar 96, the lower stud 110, (Figs. 22 and 23), thereon engages the inclined edge 109 of the lower recess 314 in the double crank 108 which is simultaneously rocked into the path of the stud 110 by the camming action of the inclined edge 103 (Fig. 16), of the link 83, on the stud 101 (Fig. 14), whereby said draw bar 96 is cammed endwise in a direction to set the draw key 114 in position to couple the forward driving gear 209 to the sleeve 117 whereby the revolutions counter RC is conditioned for addition. In the set position of said draw key 114, said stud 110 engages the lower notch 120 of the double crank 108, thereby locking said draw key 114 in set position and therefore the revolutions counter RC in adding condition.

The described rocking of the actuator rack conditioning crank 102 to subtracting position moves the link 121 rearwardly and the lever 123 counter-clockwise, from the position shown in Fig. 14, thereby rocking the overdraft conditioning bail 124 clockwise. Clockwise rocking of said bail 124 swings the overdraft flap 128 forwardly to the position shown in Fig. 18 so that the lug 130 thereon is aligned with the lug 131 of the transfer dog 132 associated with the accumulator wheel 307 of highest denomination.

In the described rocking movement imparted by the division key 16, upon its depression, to the lever 59, the spring 61 is tensioned to rock the bell crank 62 (Fig. 15), which, through lug 65, rocks the bail 66 clockwise against the tension of its spring 67, whereby through coaction of the roller 78 and arm 77, the key locking bail 80 is swung around the shaft 57 counter-clockwise. By such rocking of the bail 80, the clutch control rocker 160 (Fig. 14), through the described connections 150, 151, 153 is rocked clockwise, as viewed in Fig. 14, thereby tensioning the spring 159 and rocking the clutch control shaft 162 and clutch tripping dog 161 clockwise from their normal intermediate positions. The value entering clutch 143 is thus engaged, the carriage shift clutch 140 remains disengaged, and the motor 1 is energized, all as previously described under the heading "Add and subtract conditioning means." Incidentally, as described in the foregoing, the depressed value keys K are locked down as will be understood.

As an incident to rocking of the clutch control shaft 162, the control flap 189 (Fig. 18) is rocked on the shaft 125 by the lever arms 186, 190, counter-clockwise as viewed in Fig. 18, to the limit of its movement in this direction which is sufficient to position the upper, inclined edge of the flap 189 in line with the overdraft slide 191.

The machine now performs a cycle of operation during which the divisor "625" is subtracted from the dividend "390,625" by complemental addition and the revolutions counter RC is operated to register "1" in the counter wheel 300^a of highest denomination.

In the example given, as will be understood, no transfer occurs in the highest denomination of the accumulator A and the transfer dog 132 of highest denomination is not conditioned for transferring operation. However, as described in the

previously noted Patents Nos. 1,011,617 and 1,566,961, said dog is raised by its associated transfer cam 192 at the end of the cycle of operation of the machine. Such movement of said transfer dog rocks the overdraft flap 128 counterclockwise (Fig. 18) whereby the lug 194 (Fig. 20) of said flap depresses the overdraft slide 191. Depression of said slide 191 rocks the control flap 189 clockwise to the opposite limit of its movement, whereby the clutch control shaft 162 is rocked counterclockwise past its normal intermediate position. In the rocking of said shaft 162, as will be clear from the foregoing description, the clutch tripping dog 161 is swung into a position to effect disengagement of the value entering clutch 143 and engagement of the carriage shift clutch 140. Since the clutch control rocker 160 is held stationary by the locked division key 16 and the connections 59, 61, 62, 65, 66, 79 etc., counterclockwise movement of the clutch control shaft 162 and said dog 161 is against the tension of the spring 159, (Fig. 14). As will be understood from the previous reference to the clutch combs 201 and 260 (Fig. 5), the engagement of the carriage shift clutch 140 is not effected until the value entering clutch 143 has rotated sufficiently to complete the cycle of operation of the actuator racks R. The carrier 173 is still held, by the arm 169 of the rocker 160, in the position previously described in which the contact control lever 176 is located in its effective position relative to cam 178, 179 so that the motor 1 is still energized. Hence the carriage C is shifted one step to the left.

As soon as the transfer dog 132 (Fig. 18) is released by its transfer cam 192, the overdraft slide 191 is raised by its spring 195, and thereby releases the control flap 189. This releases the clutch control shaft 162 and clutch tripping dog 161 for return under the urge of the tensional spring 159 to effect disengagement of the carriage shift clutch 140 and engagement of the value entering clutch 143. Such operation of said shaft 162 and dog 161 is blocked by the comb 201 of the carriage shift clutch 140 until said clutch has completed its cycle of rotation, at which point the carriage shift clutch 140 is disengaged and the value entering clutch 143 engaged, as will be clear without further explanation.

It is obvious that with the division key 16 depressed, the shift of the clutch tripping dog 161 by pressure of the overdraft slide 191 on the flanged upper edge of the automatic carriage shift control flap 189, is effected against the tension of the spring 159 of the clutch tripping dog 161. This spring, therefore, is thus made effective to restore the clutch tripping dog 161 to position wherein the carriage shift clutch 140 is held idle, while the value entering clutch 143 is free to operate.

Referring now to the automatic actuator rack conditioning mechanism, it should be explained that the ratio of drive to the carriage C is such that the gears 133 and 134, (Figs. 3 and 13), and the sleeve 227 turn through half of a revolution in each step of movement of said carriage and that the eccentric 220 of said conditioning mechanism occupies low and high stroke positions in alternate half rotations of said gears. Under subtraction conditioning of the actuator racks R by said conditioning mechanism, said eccentric 220 occupies its low stroke position.

During the above-described leftward carriage step movement, the eccentric 220 moves to its high stroke position, Fig. 13, thereby rocking the

5 crank 84 and shaft 85 counterclockwise, as viewed in Fig. 14, to shift the coupling bar 83 forwardly whereby the conditioning crank 102 is rocked in a direction to set the locking bolt 99 so that the actuator racks R are conditioned for addition. Such rocking of the conditioning crank 102 rocks the shaft 107, and the crank 108 clockwise, during which rocking movement the stud 110 of the draw bar 98 remains locked in engagement with the lower notch 120 of the double crank 108, to pull the draw bar 98 forwardly, whereby the draw key 114 is set to couple the reverse gear 208 to the sleeve 117 and thereby condition the revolutions counter RC for subtraction. The slot 98 in 10 the forward end of the draw bar permits advance 15 of the draw bar relatively to the stud 97 of the arm 95, which remains stationary.

Coincidentally with the described automatic 20 conditioning of the actuator racks R for addition and the revolutions counter RC for subtraction, 25 the link 121 (Fig. 14), is shifted forwardly by the conditioning crank 102 whereby, through the lever 123, the overdraft conditioning ball 124 is swayed counterclockwise, as viewed in Figs. 14 and 18, thus rocking the overdraft conditioning lever 126 clockwise and shifting the overdraft flap 128 rearwardly from the position shown in Fig. 18, so that the lug 130 thereof is moved out of alignment with the lug 131 of the transfer dog 132 30 and the lug 207 of said flap 128 is moved alongside of said lug 131, slightly above the same. In this relation of the overdraft flap 128 and transfer dog 132, said dog operates said flap 128 only in the event that said dog executes a transfer 35 operation, in which operation as disclosed in the previously noted Patents 1,011,617 and 1,566,961, said transfer dog 132 is moved both laterally and upwardly.

In proceeding with the example given, the machine now adds the divisor "625" four times to the dividend and subtracts the value "4" in the revolutions counter RC, at which point a transfer occurs in the highest denomination of the accumulator A, or in other words, an overdraft 45 occurs. Under this condition, the lug 131 of the transfer dog 132 acts on the lug 207 of the overdraft flap 128 and again rocks the latter counterclockwise, thereby again rocking the control flap 189, the clutch control shaft 162, and clutch tripping dog 161 to effect engagement of the carriage 50 shift clutch 140 and disengagement of the value entering clutch 143, all in the manner previously explained.

The carriage C is now again shifted one step 55 to the left. In the meantime, the actuator racks R are conditioned for subtraction by the automatic actuator conditioning mechanism, the revolutions counter RC is conditioned for addition, the overdraft flap 128 is shifted to align the lug 130 with the lug 131 of the transfer dog 132 and 60 at the end of said step the value entering clutch 143 is engaged and the carriage shift clutch 140 disengaged all as will be clear from the previous explanation. It will be remembered that in this 65 relation of the overdraft flap 128 and transfer dog 132, said dog is operative against said flap 128 only when no transferring movement is executed by said dog. Therefore, as soon as this condition obtains the overdraft flap 128 is rocked by said dog 132 thereby rocking the control flap 189, the clutch control shaft 162 and the clutch tripping dog 161 to effect engagement of the carriage 70 shift clutch 140 and disengagement of the value entering clutch 143 in a manner which has been explained and need not be repeated.

The described alternate stepping of the carriage C and the operation of the actuator racks R, together with the alternate conditioning of said actuator racks and also of the revolutions counter RC, under control of the overdraft mechanism and the automatic actuator rack conditioning mechanism continues until the carriage C reaches its extreme left hand position at which point the quotient "625" appears in the revolutions counter RC.

In this left hand position of the carriage C the overdraft flap 128 is again rocked by the transfer dog 132 for reasons which it is believed will be clear. However, in this position of the carriage C the overdraft slide 191 is located over the disabling rocker 147 which is consequently rocked clockwise by said slide 191 against the tension of the spring 32. The locking bail 31 is thereby swung by said rocker 147 into unlocking position and the division key 16 released for return by its spring 45. The bell crank 50, 52, the lever 59, the bell crank 62, and the bail 66 return to normal position under the urge of springs 53, 61, 72, and 67, respectively. Return of the bell crank 62 elevates the coupling bar 83, through the medium of the suspension link 81 and thereby uncouples the automatic actuator rack conditioning mechanism from the crank 102 and consequently the actuator racks R. Return of the bell crank 50, 52 rocks the shaft 57 and 30 crank 95 back to normal position, elevating the draw bar 96 back into its normal position shown in Fig. 22. Return of the bail 66 permits return of the key locking bail 80 by the yoke 151 (Fig. 14), under the influence of the spring 151^a of the latter and the spring 159 of the clutch control rocker 160, the clutch control rocker incidentally being returned to normal position, as will be obvious, thereby returning the clutch control dog 161 and shaft 162 to their normal intermediate 40 positions, in which as previously explained, both the carriage shift clutch 140 and the value entering clutch 143 are disengaged. The return of the clutch control lever 160, as has previously been explained, permits return of the carrier 175 and the contact control lever 176 to ineffective 45 positions whereupon the contacts 141, 142 are opened and the motor 1 comes to rest.

From the foregoing description it will now be seen that during a division operation, the machine is automatically conditioned in successive left shift steps of movement of the carriage C for addition and subtraction, respectively, by the automatic conditioning mechanism and under control of the division key 16 and the overdraft mechanism. Obviously, under certain conditions, the machine may stop while conditioned by the automatic conditioning mechanism for addition. In this event, the carriage C is positioned in what corresponds to an adding location. Also the carriage reverse gearing (Fig. 13), before described is conditioned for left shift of the carriage C. Manifestly, under these conditions, a division operation could not be accomplished since the initial step in a division operation is a subtractive one.

To obviate the condition pointed out in the immediately preceding paragraph the carriage C in such event, is automatically spaced one step to the right, upon depression of the division key 16, into a subtraction location as follows. The before-mentioned eccentric 220, it will be noted, in its upstroke position (Fig. 13), positions the coupling bar 83 at its forward limit of travel to condition the actuator racks R for addition and, 75

in its lower stroke position, positions said coupling bar rearwardly to condition said actuator racks for subtraction. The coupling link 81 is swung by said coupling bar 83 to move its coupling lug 86 into and out of the notch 93, (Fig. 16), of the coupling link 88 in the forward and rearward positions of said bar, respectively. It will be remembered that the coupling link 88 depends from the key lever 90 of the carriage right shaft key 15. Consequently the carriage right shift key lever 90 is coupled to said bell crank 62 under adding conditioning of the actuator racks R by depression of the division key 16, the coupling link 81 being uncoupled from the carriage right shift key lever under subtraction conditioning of said actuator racks.

With the lug 88 of the coupling link 81 engaged with the depending coupling link 88, in an additive conditioning of the machine the division key 16 upon depression, will draw with it the carriage right shift key lever 90 the division key lever 42 picking up the bell crank lever 62 through the before described connections of the lug 58, the lever 59 and the spring 61. In this connection, it is to be noted that complete depression of the carriage right shift key lever 90 occurs under partial depression of the division key 16, the arrangement of the links 81, 88 and the bell crank 62 being such as to accomplish this result, and the spring 61 providing a yielding connection between the key lever 42 and the bell crank lever 62 whereby said key lever 42 may be completely depressed and locked down by the bail 31. Upon depression of the carriage right shift key lever 90, the carriage reverse gearing is conditioned to shift the carriage to the right in the manner previously described under the heading "Carriage shift right and left." As will of course be understood, all the operations, previously described as following upon depression of the right shift key 90, occur, including the engagement of the carriage shift clutch 140.

Upon complete depression of the division key lever 42, such operations previously described as incident thereto occur such as closing of the motor contacts 141, 142, by rocking of the clutch control rocker 160 and tensioning of the spring 159 of said rocker, whereby the clutch control dog 161 is urged in the proper direction to effect engagement of the value entering clutch 143 and disengagement of the carriage shift clutch 140. It will be remembered, however, that movement of the clutch control dog 161 to engage the value entering clutch 143 cannot occur until the carriage shift clutch 140 has executed a complete revolution by virtue of the comb 201 of the carriage shift clutch 140 blocking such movement thereof. The carriage C now shifts to right until the eccentric 220 reaches its lower stroke position. At this point the carriage C has shifted to right one step into a subtracting position, the actuator racks R are conditioned for subtraction, the revolutions counter RC conditioned for addition and the coupling link 81 is uncoupled from the coupling link 88 thereby releasing the carriage right shift key lever 90 for return under the urge of its spring 236. In the return position of the key lever 90, the lower cam edge 237 (Fig. 22), of the coupling link 88 rises above the lug 86 of the link 81 whereby, when the bell crank lever 62 is returned, the coupling link 81 is cammed into proper coupling relation to the link 88 by co-action of said cam edge 237 and lug 86 under the urge of the spring 91. Also in the raised position of the coupling link 88 the coupling link

81 may swing independently of link 88 when the coupling bar 83 is coupled to the crank 102 for a purpose which will be clear. During the movement of the eccentric 220 to its lower stroke position, or in other words, during the step of movement of the carriage shift C, the carriage clutch has rotated sufficiently to permit the clutch control dog 161 to move, under the urge of the spring 159, into the proper position to disengage said carriage shift clutch 140 and engage the value entering clutch 143.

Prior, however, to the operations occurring upon depression of the division key lever 42, the bell crank 229 (Fig. 21), related to the carriage right shift key lever 90 has returned to normal position with said key lever 90, and the lug 233 of said bell crank has released the crank member 235 of the clutch control shaft 162 to free the shaft for operation. Incidentally the return of the bell crank 229 to normal position by its spring 236, has permitted the draw key 139 to be set for left hand driving of the carriage C under the urge of the spring 223 and through operation of the bell crank 136, levers 231, 233, 226 comprising the gear conditioning unit, the link 203 and the draw key setting lever 224. Division now proceeds as regards remaining operations in the manner previously described in detail. In the right hand position of the carriage C, its abutment 135 (Fig. 21) acts on the lever 136 and rocks the same in the clockwise direction. Thereby, through the intermediary of the parts 233, 231, 203 and 224, the key 138, 139 (Fig. 13), is shifted to the left, coupling the carriage left shift gear 134 with the bushing 227. This position of the parts is retained even if the carriage abutment 135 (Fig. 21) removes from the lever 136 on account of the fact that, in any position of the carriage C, other than its extreme left hand position, the spring 223 retains the lever 136 locked in the clockwise direction. In the extreme right hand position of the carriage C, the eccentric 220 (Fig. 13) of the right shift wheel 133 is displaced through 180° from the position shown in Fig. 13, to its lower (subtractive) position, so that through the parts 202, 203, 85 and 84, the coupling bar 83 is displaced in the direction of the arrow x (Figs. 13 and 15). Consequently, the coupling link 81 jointed to the coupling bar 83 (Fig. 15), is rocked in anti-clockwise direction to unseat the lug 86 of the coupling link 81 from the recess 93 of the companion coupling link 88, and thus disconnect the coupling links 81 and 82. If the division key 16 is depressed while the parts are in the foregoing positions, the lug 86 of the coupling link 81 does not act upon the lug 88b of the coupling link 88 and the carriage right shift key 15 will not be depressed.

QUOTIENT DIFFERENCE DIVISION

The operation of quotient difference division is concerned principally with obtaining the difference between quotients of different division problems. Let it be assumed for instance, that the problem " $390,625 \div 625$ "—" " $12,500 \div 625$ "—is to be solved, the first performance of the part of the problem having been already explained. At the end of the performance of the problem " $390,625 \div 625$ " the quotient "625" appears in the revolutions counter RC with the digit of highest denomination in the counter value wheel 300 next to that of highest denomination. The divisor "625," for the purposes of illustration, is

still set up in the value selecting mechanism and key board.

In performing the rest of the problem the carriage C is again shifted into its extreme right hand position under control of the carriage right shift key 15. The dividend "12,500" is now set up in the accumulator A by means of the knobs 311, to avoid altering the quotient values "625," and with the digit of highest denomination in the counter wheel 300 of next highest denomination, so that the dividend and quotient digits of highest denomination are properly related. Obviously it is unnecessary with the example given, to set up the divisor "625" since this set up remains in the machine.

The quotient difference division key 18 is now depressed thereby swinging the key lever 23 thereof clockwise as viewed in Fig. 15, and, through coaction of said key lever and the lug 38 of yoke 40, similarly swinging the latter. The yoke 40 in its swinging movement similarly swings the lever 59 by coaction of the yoke arm 41 with the lug 58 of said lever. The lever 59, through the spring 61, simultaneously swings the bell crank lever 62 clockwise, against the tension of the spring 71. The key locking bail 31 coacting with the notch 30 in the quotient difference division key lever 23, locks said lever depressed and the yoke 40 and lever 59 in the positions into which they are swung. Upon the swinging of the bell crank 62, the coupling of the coupling bar 83 to the crank 102 follows, whereby the actuator racks R are conditioned for subtraction, as previously described, and the state control rock shaft 107 is rocked counterclockwise, as viewed in Fig. 14, whereby the double crank 108 is rocked counterclockwise into the position shown in Fig. 24. The rocker 50 is not effected by depression of the quotient difference division key 18. Hence the rocking of the shaft 57 and crank 95 previously described, as effected under control of the division key 16, does not occur, and said crank 95 remains fixed in the position illustrated in Fig. 24. As a result, the upper stud 290 of said draw bar 96 remains engaged with the upper notch 291 of the double crank 108 and the draw bar 96 is moved forwardly to condition the revolutions counter RC for subtraction, in the manner previously described in detail.

Coincidentally with the conditioning of the actuator racks R and the revolutions counter RC for subtraction, the conditioning flap 124 is swung by the crank 102 to shift the overdraft flap 128 rearwardly, and thereby condition the overdraft mechanism, and the bail 66 is actuated by the bell crank 62 to rock the key locking bail 80 and thereby swing the clutch control rocker 160 to tension the spring 159 and rock the clutch control dog 161 to effect engagement of the value entering clutch 143, said rocker effecting the closing of the motor contacts 141, 142, all in the manner described with reference to the division operation. Also, on the arrival of the carriage C into its extreme right hand position, the carriage reverse gearing is automatically conditioned for left hand shift of said carriage, through the mechanism and as described in connection with the division operation.

We now have the machine conditioned for division except that the revolutions counter RC which is in subtractive condition. Since, under depression of the quotient difference division key 18, the machine operations are substantially the same as those previously described under the heading "Operation of division," with the ex-

ception of those occurring in the revolutions counter RC, the different operation of said revolutions counter only will be described.

Upon completion of the first cycle of operation of the machine, the counter wheel 300^a of highest denomination is rotated subtractively from "0" to "9" so that the revolutions counter RC shows the value "96250000." The carriage C is now shifted one step to the left under control of the overdraft flap 128 which, it will be remembered, is operated by the transfer slide 132 to control engagement and disengagement of the carriage shift value entering and clutches 140, 143. Also, it will be remembered that, at this point, the condition of the accumulator A and revolutions counter RC is reversed as regards to their previous conditioning. Hence, addition now occurs in both, and in the following cycle of operation of the machine, the counter wheel 300^a of the seventh denomination is rotated ten steps of movement additively resulting in a transfer operation in said counter to the counter wheel 300^a of the eighth denomination, which is thereby rotated from "9" to "0". The revolutions counter RC now shows the value "06250000." At this point, the carriage C is again shifted one step to the left, the overdraft flap 128 having again been operated previously by the transfer slide 132. During this step of movement of the carriage C the accumulator A and the revolutions counter RC are conditioned for subtraction.

In the next cycle of operation the counter wheel 300 of the sixth denomination is rotated subtractively three steps thereby passing through zero and causing a transfer to the counter wheel 300^a of the seventh denomination which thereupon shows "5". In the revolutions counter we now have the value "05950000". The carriage C again steps to the left and the accumulator A, revolutions counter RC are conditioned for addition, and the machine performs a cycle of operation in which the counter wheel 300^a of the fifth denomination is rotated ten steps additively, thereby passing through zero and causing a transfer to the counter wheel 300^a of the sixth denomination. The transfer to the sixth denominational counter wheel causes the same to rotate from "9" to "0" and to thereby cause a transfer to the counter wheel of the seventh denomination whereby the latter is rotated from "5" to "6".

The revolutions counter RC now shows the value "06050000," the correct result. However, the machine continues in operation until the carriage reaches its extreme left hand position. In the next step of movement of the carriage C the accumulator A and revolutions counter RC are conditioned for subtraction. In the succeeding cycle of operation the value wheel of fourth denomination is rotated from "0" to "9" causing, a transfer to the value wheel of fifth denomination which is thereby rotated from "5" to "4" so that the revolutions counter RC now shows "06049000." Again the carriage steps to the left and again said accumulator A and revolutions counter RC are conditioned for addition. In the next cycle of operation the counter wheel of the third denomination is rotated through ten steps additively, thereby passing through zero and causing a transfer to the counter wheel of fourth denomination whereby the latter is rotated from "9" to "0," causing a transfer to the wheel of fifth denomination which is thereby rotated from "4" to "5". The revolutions count-

er RC now shows "06050000." Another step of movement of the carriage to the left occurs and said accumulator A and revolutions counter are conditioned for subtraction. In the following cycle of operation the revolutions counter shows the value "06049990". The carriage then again steps to the left and said accumulator A and counter RC are conditioned for addition. Another cycle of operation follows, the counter wheel of first denomination is rotated ten steps, whereby it passes from "9" to "0," causing a transfer to occur through the wheels of second, third and fourth denomination to the wheel of fifth denomination whereby the latter is rotated one step from "4" to "5." The revolutions counter RC now again shows the value "06050000," the correct result.

The carriage C is now in its extreme left hand position in which, as before described, the locking ball 31 is swung to releasing position by operation of the disabling flap 147. The quotient difference division key 18 is thus released and the machine is brought to rest in the manner previously described.

As will be clear, if the carriage C is in an adding position, upon depression of the quotient difference division key 18, the same results are obtained through operation of the yoke 40 as described with reference to the division key 16 when the carriage C is in such a position.

The foregoing constitutes a detailed description of a preferred embodiment of my invention. It is to be understood, however, that the right is herein reserved to make changes in details and arrangements of parts falling within the scope of the claims appended hereto.

What I claim is:

1. In a calculating machine, the combination with a carriage, accumulator wheels on said carriage, and transfer dogs operated during each additive or subtractive cycle of operation of the machine, actuator racks for said accumulator wheels, a special control key, a motor drive, including a carriage shift clutch for moving said carriage step by step and a value entering clutch for operating said actuator racks, of means for rendering said clutches effective alternately under control of said special key and the transfer dog of the accumulator wheel of highest denomination; said last-mentioned means including a swingable clutch control member in the machine frame, a normally ineffective device on said carriage adapted to travel along said member and operable by said transfer dog to swing the member, means for operatively relating said device to said dog, and a second swingable member on said frame, and connected to said relating means in each position of the carriage and swingable in one direction to move said relating means into operative relation to said dog as an incident to depression of said special key.

2. In a calculating machine, the combination with a carriage, an accumulator on said carriage, and including accumulator wheels and transfer dogs operative during each additive or subtractive cycle of operation of the machine, actuator racks for said accumulator, a special control key, a motor drive, including a carriage shift clutch for moving said carriage step by step, and a value entering clutch for operating said actuator racks, of means for rendering said clutches effective alternately under control of said key and the transfer dog of the accumulator wheel of highest denomination, and including a clutch control member swingable on the ma-

chine frame, devices on said carriage travelling along said member and movable into operative relation to said transfer dog by depression of said special key for operation by said dog to swing said member, means operable by said key, when depressed, to so move said devices, a lock for retaining said special key depressed, and means operated by said devices for releasing said lock at the end of the carriage run.

3. In a calculating machine, the combination with a carriage; an accumulator mounted in, and travelling with the carriage; transfer mechanism for the accumulator; actuating means for the accumulator; a motor drive for the actuating means; and settable state control means to condition the actuating means for additive or subtractive operations; of a carriage shift mechanism to shift the carriage and accumulator denominational; an eccentric operable incident to the operation of the carriage shift mech-

anism; normally ineffective means operable by the eccentric to set the state control means alternately to its additive and subtractive positions as the carriage is shifted to successive 5 denominational positions; a division key, a motor drive for the actuating means and for the carriage shift mechanism; means controlled by the division key to cause the motor drive to operate the actuating means, and to render the normally 10 ineffective means effective; and means controlled by the transfer mechanism to terminate the operation of the actuating means, and to cause operation of the carriage shift mechanism by the motor drive to shift the carriage to 15 the next lower denominational position and so to cause the eccentric to operate the normally ineffective means to reverse the setting of the state control means.

20

AUGUST FRIEDRICH POTT.
